TURBINE PUMP

Garrett E. Masure, Sepulveda, Calif., assignor to Westinghouse Electric Corporation, East Pittsburgh, Pa., a corporation of Pennsylvania

Filed Oct. 3, 1958, Ser. No. 765,178

6 Claims. (Cl. 103—2)

This invention relates to rotary pumps of the turbine or regenerative type and has for an object to provide an improved pump of this type.

Turbine pumps have high pressure developing capacity even at relatively low speed, because of the recirculating action between the blades of the impeller and the walls of the pressure developing chamber, as well as the resultant accumulation of energy in the fluid during its travel between the suction inlet and discharge outlet. However, the maximum fuel flow (delivery) capacity of the pump is attained at relatively low speeds and may be insufficient for many applications.

In view of the above, it is a further object to provide a fluid pump of the turbine type which has a high pressure developing capacity at relatively low speeds and has a high fuel delivery capacity at higher speeds.

Another object of the invention is to provide a fluid pump of the turbine type in which the fluid flow and fluid pressure developing characteristics of the pump are modified in response to a predetermined speed signal.

In accordance with the invention, there is provided a turbine pump having an impeller provided with a pair of annular rows of radial blades and disposed within a housing which, jointly therewith, defines a symmetrical annular pressure developing chamber or passageway. The pump is further provided with the usual peripherally spaced primary suction inlet and primary discharge outlet for the pressure developing chamber.

A secondary suction inlet and a secondary discharge outlet are also provided for the chamber and are disposed intermediate the primary inlet and outlet. The secondary inlet and outlet are blocked in the low speed range by valve structure, so that the pump operates in the conventional manner in the low speed range to deliver fluid at adequate pressure and flow rate.

Means responsive to speed of the impeller is provided for actuating the valve structure to the unblocking position at a predetermined speed value. Accordingly, in the upper speed range, fluid is admitted to the pressure developing chamber by the primary and secondary suction inlets and delivered therefrom at increased flow rate by the primary and secondary discharge outlets. Since, in the upper speed range, the length of the fluid path through the chamber is considerably reduced, the pressure developed by the fluid flowing therethrough is considerably less than that developed by a conventional turbine pump in the same speed range. However, since the pump inherently has excessive pressure developing capacity, the developed pressure is more than adequate for practical applications.

One of the most notable applications, for example, is in a gas turbine engine wherein the pump is driven by the engine rotor for supplying liquid fuel thereto within prescribed pressure and flow rate ranges for combustion purposes at varying rates of speed (for example, from about 1400 r.p.m. to 12,500 r.p.m.). In such an appli-

2

cation, the speed responsive means may be desirably adjusted to unblock the secondary inlet and outlet of the pump at about 5000 r.p.m., which speed is the idling speed of the engine.

5 The above and other objects are effected by the invention as will be apparent from the following description taken in connection with the accompanying drawings, forming a part of this application, in which:

Fig. 1 is a diagrammatic view illustrating a typical gas 10 turbine engine having a fuel pump embodying the invention, the pump being shown in one operative position;

Fig. 2 is a view showing the pump in another operative position;

Fig. 3 is an enlarged sectional view taken on line III—III of Fig. 2; and

Fig. 4 is a chart showing a number of characteristic operating curves.

Referring to the drawing in detail, especially Fig. 1, 20 there is shown a gas turbine engine 10 equipped with a fuel pump 12 of the turbine type, formed in accordance with the invention.

The gas turbine engine 10 forms no part of the invention and has been shown merely to illustrate a typical 25 application for the pump. In the example shown, the gas turbine engine is of the well-known axial flow aviation turbojet type having a tubular outer casing 13 within which are disposed an axial flow compressor 14 having a rotor 15, fuel combustion apparatus including an annular combustion chamber 16 equipped with a plurality of fuel injecting nozzles 17, and an axial flow gas turbine 18 having a rotor 19 drivingly connected to the compressor rotor 15 by a drive shaft 20. The casing 13 defines a forwardly directed air intake opening 21 and a rearwardly directed exhaust nozzle 22.

In operation, fuel is admitted to the fuel injecting nozzles 17 by a delivery conduit 23 and injected into the combustion chamber 16 where it is ignited in the presence of pressurized air to provide hot motive gases for the turbine 18. After partial expansion in the turbine to drive the turbine rotor 19, the gases are ejected through the exhaust nozzle 22 in a rearwardly directed propulsive jet. The turbine rotor, in turn, drives the compressor rotor 15, whereby atmospheric air is drawn through the air intake 21 and delivered in a pressurized state to the combustion apparatus to complete the cycle.

The fuel pump 12 is provided with an impeller 25 having a pair of annular rows of circumferentially spaced radial blades 26 and a housing 27 fitting snugly about 50 the impeller and jointly therewith defining an annular fluid pressure developing chamber 28 of symmetrical shape. The impeller 25 is carried by a rotatably supported drive shaft 29 which is drivingly connected to the turbojet engine rotor aggregate by gearing 30.

55 Hence, the impeller 25 is rotated at varying speeds as determined by the speed of the turbojet engine, in one direction, for example, clockwise, as illustrated.

The housing 27 provides a primary suction inlet 31, connected to a suitable fuel supply source 32 by conduit 33, and a primary discharge outlet 34, connected to the engine fuel delivery conduit 23. The discharge outlet 34 is peripherally spaced from the suction inlet 31 to a large angular degree in the direction of impeller rotation, and in the example shown, the angular spacing is about 250 65 degrees.

In addition thereto, the pump housing 27 is further provided with annular wall structure 35 defining a bypass passageway 36, communicating at its downstream end with the delivery conduit 23, and at its upstream 70 end with a secondary discharge outlet 37. Extending through the bypass passageway 36 is a hollow strut 38

defining a secondary suction intake 39. The secondary intake 39 is connected to the fuel supply conduit 33 by a conduit 40 disposed externally of the pump housing 27.

The primary and secondary inlets 31 and 39 are arranged to admit the fuel directly to the annular chamber 28, while the primary and secondary outlets 34 and 37 are arranged to eject the fuel directly from the chamber 28.

A pair of solenoid valves 41 and 42 having movable valve members 43 and 44, respectively, are provided for controlling the secondary suction intake 39 and the secondary discharge outlet 37, respectively. The valves 41 and 42 are formed in such a manner that when they are de-energized their valve members 43 and 44 are disposed in the flow blocking position, as illustrated in Fig. 1, thereby preventing fuel flow into the suction intake 39 and from the discharge outlet 37. Hence, with the valves in this position, the fuel from the supply conduit 33 flows through the primary suction intake 31 into the pump chamber 28 and traverses an angular path of about 250 degrees before ejection through the primary discharge outlet 34.

The solenoid valves 41 and 42 are controlled by an electrical control system including a suitable switch 46 responsive to the rotational speed of the impeller shaft 29. The speed responsive switch 46 is connected into the electrical system in series with a suitable source of E.M.F. 47 and the solenoid valves 41 and 42 are connected in parallel. Also, if desired, a manually operable switch 48 may be provided for conditioning the system for automatic operation when desired. The speed responsive switch 46 is arranged in a manner to interrupt the circuit through the solenoid valves 41 and 42 at impeller shaft speeds below a preselected speed valve and to complete the circuit upon attainment of the selected speed by the shaft. Hence, when the engine 10 is operating at a speed below the selected value (low speed range), the fuel pump is conditioned as illustrated in Fig. 1, whereas above said selected value (upper speed range), the solenoid valves 41 and 42 are energized and their valve members 43 and 44, respectively, are moved to the unblocking position as illustrated in Fig. 2.

When the fuel pump is conditioned as shown in Fig. 2, fuel from the fuel supply is directed through the supply conduit 33 to the fuel pump through the primary suction inlet 31 and by the conduit 40 through the secondary inlet 39. Hence, the fuel admitted to the fuel pump through the primary suction inlet 31 is translated through the pressure developing chamber 28 in an arcuate path of about 90 degrees and is then ejected from the chamber through the secondary suction outlet 37. This fluid stream is then directed through the bypass passageway 36 to the fuel delivery conduit 23. In a like manner, the fuel admitted to the chamber 28 through the secondary suction intake 39 is translated through an arcuate path of about 90 degrees before ejection through the primary discharge outlet 34, from whence it joins the fuel stream flowing through passageway 36 and is directed through the delivery conduit 23 to the fuel injecting nozzles.

Accordingly, in the low speed range for the turbojet engine, with the speed responsive switch 46 in the circuit interrupting position and the manual switch 48 in either the open or closed position, the fuel is fed to the engine after traversing the fuel pump chamber 28 in one single path of large angular extent, so that although the fuel flow rate is moderate, the fuel pressure is relatively high.

In the upper speed range, wherein the speed responsive switch 46 is in the circuit making position, with the manual switch 48 in the closed position, the fuel is delivered to the engine after traversing the fuel pump chamber in two separate streams through angular paths of individually less extent than the first mentioned path. Hence, the fuel flow rate is considerably higher while the fuel pressure value is reduced in proportion.

Since, as well known in the art, the engine 10 demands

relatively low fuel flow rates in the low speed range and considerably higher fuel flow rates in the upper speed range, the fuel pump will satisfactorily fulfill the fuel demands of the engine.

The following more specific analysis serves to more fully outline the performance characteristics of the fuel pump for varying operation of the turbojet engine 10.

The turbojet engine 10, for example, may have the following representative fuel pressure and fuel consumption requirements, as shown in the chart in Fig. 4.

	Fuel Pressure in p.s.i.	Fuel Consumption in p.p.h.
During starting (12% Rated Speed)	50	400
Idling Speed (40% Rated Speed)	100	770
Rated Speed	400	3,600

In the upper speed range, between idling and rated speed, the fuel requirements of the engine are illustrated by the curve A.

By further reference to the chart shown in Fig. 4, curve B illustrates the low speed range fuel pumping characteristics of the fuel pump with the solenoid valves 41 and 42 in the flow blocking position. Curve B rises rather sharply and at about 1400 r.p.m. the pump discharge pressure is about 55 p.s.i. while at about 5000 r.p.m. the pressure is about 675 p.s.i. Since the 1400 r.p.m. coincides with the starting r.p.m. of the engine, it will be noted that the pump discharge is adequate to satisfy the engine fuel pressure requirements in this range. However, at 5000 r.p.m., coinciding with the engine idling speed, the pump pressure is considerably above that required by the engine.

Curve C illustrates the upper speed range fuel pumping characteristics of the fuel pump with the valves in the unblocking position. It will be seen that when the speed responsive switch 46 energizes the valves 41 and 42 to the unblocking position, as indicated by vertical dotted line D, the pressure value drops to about 100 p.s.i. but the fuel flow rate of 770 p.p.h. is maintained during such change in conditioning of the pump. Thereafter, as the r.p.m. of the impeller increases, the fuel pressure again rises in a gradual manner with concomitant increase in fuel flow rate.

By comparing curves B and C with the engine requirements mentioned above and curve A, it will readily be seen that the fuel pump is capable of satisfying the engine fuel requirements in the low as well as the upper speed range. Also, in the upper speed range, the fuel pressure at the pump outlet is maintained at reasonable, yet not excessively high, values above the engine requirements.

It will now be seen that the invention provides a highly improved and versatile pump of the turbine type which may be reliably employed as the main fuel pump of a fuel combustion engine, such as a turbojet engine.

It will further be seen that the invention provides a turbine type fluid pump having dual flow and pressure output characteristics which lends itself to applications wherein it is driven at variable speed through a relatively wide range of speeds.

While the invention has been shown in but one form, it will be obvious to those skilled in the art that it is not so limited, but is susceptible of various changes and modifications without departing from the spirit thereof.

What is claimed is:

1. In combination, a pump comprising an impeller of the turbine type having a circumferential row of radially extending blades, housing structure surrounding said impeller and jointly therewith defining an annular fluid pressurizing chamber, said housing structure defining a first suction inlet and a first discharge outlet, a second suction inlet and a second discharge outlet; said inlets and outlets communicating directly with said chamber, means for driving said impeller in one direction at varying speeds

of rotation, said first inlet and outlet being angularly displaced in the direction of rotation to a greater degree than said second outlet and inlet, valve structure for blocking and unblocking said second inlet and outlet, and means responsive to speed of rotation of said impeller for controlling said valve structure, said speed responsive means being effective to maintain said valve structure in the blocking position below a predetermined speed and to move said valve structure to the unblocking position above said predetermined speed.

2. In combination, a pump comprising an impeller of the turbine type having a circumferential row of radially extending blades, housing structure surrounding said impeller and jointly therewith defining an annular fluid pressurizing chamber, said housing structure defining a first suction inlet and a first discharge outlet, a second suction inlet and a second discharge outlet; said inlets and outlets communicating directly with said chamber, means for rotating said impeller in one direction at varying speeds, said first inlet and outlet being angularly displaced in the direction of rotation to a greater degree than said second outlet and inlet, valve structure for blocking and unblocking said second inlet and outlet, and means responsive to speed of rotation of said impeller for controlling said valve structure, said valve structure being biased in a direction to block said second inlet and outlet, and said speed responsive means being effective to move the valve structure to an unblocking position in response to a predetermined speed.

3. In combination, a fluid pump comprising an impeller of the turbine type having a circumferential row of radially extending blades, means for driving said impeller in one direction at varying speeds of rotation including a low speed range and a high speed range, housing structure surrounding said impeller, said housing structure and said impeller jointly defining an annular fluid pressurizing chamber, said housing structure further defining a first suction inlet, a first discharge outlet, a second suction inlet and a second discharge outlet, all of said inlets and outlets directly communicating with said chamber; said first inlet and outlet being angularly displaced in the direction of rotation of said impeller to a greater degree than said second outlet and inlet, said second outlet being disposed upstream of said second inlet relative to fluid flow through said chamber, valve structure for blocking and unblocking said second inlet and outlet, said valve structure blocking said second inlet and outlet said low speed range, and means responsive to speed of rotation of said impeller for jointly controlling said valve structure, said speed responsive means being effective to move said valve structure in unblocking direction in response to a predetermined speed, in said high speed range.

4. In combination, a fluid pump comprising an impeller of the turbine type having a circumferential row of radially extending blades, a housing enclosing said impeller and jointly therewith defining an annular fluid pressurizing chamber, said housing having a main suction inlet and a main discharge outlet, said housing further including wall structure defining an arcuate flow passage disposed externally of said impeller and communicating with said main discharge outlet, means defining a secondary suction inlet communicating with said impeller intermediate said main inlet and outlet, said housing providing a secondary discharge outlet communicating with said flow passage, electrically actuated valve structure for blocking and unblocking said secondary inlet and outlet, means for driving said impeller at varying rates of rotational speed, and

means including a switch responsive to speed of said driving means for jointly controlling said valve structure, said switch means being operative to effect movement of said valve structure from the blocking position to the unblocking position above a predetermined speed, thereby to increase the fluid flow rate and decrease the fluid pressure at said main discharge outlet.

5. In combination, a fluid pump comprising an impeller of the turbine type having a circumferential row of radially extending blades, a housing enclosing said impeller and jointly therewith defining an annular fluid pressurizing chamber, said housing further defining a main suction inlet and a main discharge outlet communicating directly with said chamber, wall structure defining an arcuate flow passage disposed in bypass relation with said chamber and communicating with said main discharge outlet, means defining a secondary suction inlet communicating directly with said chamber intermediate said main inlet and outlet, means defining a secondary discharge outlet connecting said chamber and said flow passage, said secondary outlet being disposed intermediate said primary and secondary inlets, electrically actuated valve structure for blocking and unblocking said secondary inlet and outlet, means for driving said impeller at varying rates of rotational speed, and means including a switch responsive to speed of said driving means for jointly controlling said valve structure, said switch means being operative to effect movement of said valve structure from the blocking position to the unblocking position above a predetermined speed, thereby to increase the fluid flow rate and decrease the fluid pressure characteristics of the pump.

6. In combination, a fluid pump comprising an impeller of the turbine type having a circumferential row of radially extending blades, a housing enclosing said impeller and jointly therewith defining an annular fluid pressurizing chamber, said housing having a main suction inlet and a main discharge outlet, said housing further including wall structure defining an arcuate flow passage disposed externally of said impeller and communicating with said main discharge outlet, means defining a secondary suction inlet communicating directly with said impeller intermediate said main inlet and outlet, said housing providing a secondary discharge outlet communicating with said flow passage, electrically actuated valve structure for controlling fluid flow through said secondary inlet and outlet, means for biasing said valve structure to the position blocking said secondary inlet and outlet, means for driving said impeller at varying rates of rotational speed, and means including a switch responsive to speed of said driving means for jointly controlling said valve structure, said switch means being operative to effect movement of said valve structure from the position blocking said secondary inlet and outlet to the position unblocking said secondary inlet and outlet at a predetermined speed and to maintain said valve structure in the unblocking position at speeds above said predetermined speed, thereby to increase the fluid flow rate and decrease the fluid pressure at said main discharge outlet.
